Primary Examiner — Darlington Ly*Assistant Examiner* — Jeremy Koenig(74) *Attorney, Agent, or Firm* — Varnum LLP(57) **CLAIM**

The ornamental design for a wheel as shown and described.

DESCRIPTION

FIG. 1 is a front perspective view of a wheel;

FIG. 2 is another front perspective view of a wheel;

FIG. 3 is a front elevation view of a wheel;

FIG. 4 is a rear elevation view of a wheel;

FIG. 5 is a rear perspective view of a wheel; and, FIG. 6 is a side elevation view of a wheel, wherein the top and bottom plan views of the wheel are identical thereto and the opposite side elevation view of the wheel is a mirror image thereof.

All broken lines illustrate subject matter, structure, and/or features of the wheel that form no part of the claimed design. The dot-dash broken lines illustrate the bounds of the claim and form no part of the claimed design.

1 Claim, 6 Drawing Sheets(56)
